UNITED STATES PATENT OFFICE.

HENRY ROBERTS, OF PITTSBURG, PENNSYLVANIA.

ROD-MILL.

SPECIFICATION forming part of Letters Patent No. 392,365, dated November 6, 1888.

Application filed May 12, 1888. Serial No. 273,709. (No model.)

To all whom it may concern:

Be it known that I, HENRY ROBERTS, of Pittsburgh, in the county of Allegheny and State of Pennsylvania, have invented a new and useful Improvement in Rod-Mills; and I do hereby declare the following to be a full, clear, and exact description thereof.

In rolling metal rods in a mill as now commonly practiced it is customary to employ a series of trains of rolls set in line with each other and to pass the metal back and forth between these rolls. As the metal is reduced in diameter and increased in length, there is always difficulty in controlling it and preventing it from kinking, especially so when it is attempted to roll more than one rod at a time in a single mill. For this purpose it has been usual to employ boys, who stand with hooks opposite to the rolls and guide the elongating metal loop, with a view of preventing it from kinking or injuring the workmen. The work of these boys is very dangerous and requires the closest attention, and therefore the wages paid them are quite high. Besides this, the least neglect on their part is apt to cause the kinking of the rod, and when this happens the delay in its passage through the mill chills the metal and unfit it for use, necessitating the cutting of it into pieces for scrap.

The object of my invention is to diminish these evils and to provide means for guiding the metal loop as the rod is passing from one set of rolls to the next.

To this end it consists, mainly, in the combination, with two sets of rolls arranged on different lines of feed, of an inclined mill-floor common to said rolls, whether the same be used either with or without an overfeed regulator leading from the rolls to the inclined floor of the mill, or with or without a guide arranged on the floor, as shown by me in the drawings, and the inclination of the floor being in a direction transversely to the axes of the rolls and being such that as the metal loop elongates it shall be forced by the action of the primary rolls away from the rolls down the inclined floor, on which it travels freely, thus preventing kinking and lessening the labor necessary to be employed in guiding it.

I am aware that in Letters Patent No. 351,836 there is described a rod-mill wherein the rod is passed between pairs of rolls separated from

each other and set so that the rod shall pass in a straight line from one pair to the next, between which pairs of rolls is a guide set on the apex of a table, which is located intermediate between the rolls, and is inclined laterally in both directions from the guide, the purpose being, as stated by the patentee, that the incline of the table laterally permits the gravity or weight of the overfeed of the rod to act in assisting its distribution over the surface, and to obviate tangling of the loops as they are drawn in by the rolls of the second or supplementary train. This device is, however, quite different from mine, because, whereas I incline the floor transversely to the axes of the pairs of rolls and use the motive force of the primary rolls as a direct agent in the propulsion of the loop down the incline, the incline of the floor of the patent referred to, being lateral, does not make use of any such positive propelling force, but, as stated by the patentee, it depends for its efficiency only on the gravity of the overfeed.

By the expression "rolls having different lines of feed" as used by me I intend to designate a mill wherein the wire as it emerges from one pair of rolls is reflexed and brought back in a loop to the next pair of rolls, thus distinguishing it from a mill wherein the rod passes in a direct course from one pair of rolls to the next succeeding pair. It does not necessarily mean that the adjacent pairs of rolls shall have their axes literally in the same line or driven by the same power-shaft.

Second. My invention consists, broadly, in a channel or guide sunk in the floor of the mill, said channel or guide being open to permit free lateral escape or overfeed of the rod, the purpose of the guide being to direct the wire.

Third. In such a guide in connection with two pairs of rolls arranged, as above stated, to guide the primary branch of the wire loop. Heretofore such guides have been set upon the floor of the mill and their sides have necessarily been above the level of the floor. The effect is sometimes to bend the wire rod as it extends over the side of the guide, and thus to cause kinking. When the guide is sunk in the floor this is not the case.

Fourth. My invention consists in a mill-floor inclined and provided with sets of rolls, as before stated, said inclined mill-floor having a

guide adapted to direct the course of the primary branch of the loop as it travels over the floor.

Fifth. In a guide of any form which is both downwardly inclined from the rolls and also obliquely inclined for the purpose of better guiding the course of the loop.

Sixth. In the combination, with two sets of rolls arranged on different lines of feed, of a single branch guide trough or channel having a flat bottom arranged on or in the mill-floor, and extending from the delivery side of the primary set of rolls over the floor in a transverse direction from the rolls, whereby the primary branch is confined and guided and permitted by the flat bottom of the trough to have a free zigzag course limited laterally by the sides of the trough, while the return branch is permitted an unobstructed travel on the floor.

Seventh. In a fender or guard-plate which is situate at the receiving side of a pair of rolls to prevent flying up of the end of the rod as it passes through. Heretofore the tendency of the rod to fly up as the end passes into the rolls has been a fruitful cause of accidents to the roller, and where more than one rod is being rolled at once in a single mill the danger often deters the roller from properly guiding the forward end of the second or third rod into the bite of the rolls. The consequence is that the work of rolling is retarded and there is apt to be a large percentage of the metal lost in scrap.

With the use of my improved fender the workman can tend his rolls with perfect security from danger of this kind, and the work can therefore progress more rapidly.

The advantages of these several features are so great that with their use I have been enabled to roll three rods at once in a single mill. It has heretofore been the usual practice to roll only one rod at a time, seldom as many as two.

The invention is illustrated in the accompanying drawings, in which—

Figure 1 is a plan view of a rod-rolling mill constructed according to the principles of my invention. Fig. 2 is an enlarged vertical longitudinal section on the line $x-x$ of Fig. 1. Fig. 3 is an enlarged vertical cross-section on the line $y-y$ of Figs. 1 and 2, showing the guide-trough and the fender. Fig. 4 is an enlarged vertical cross section on the line $z-z$ of Fig. 1.

Like symbols of reference indicate like parts in each.

In the drawings, 2, 3, 4, and 5 represent pairs of rolls of a wire-rod mill. 6 is the floor of the mill on the delivery side of the rolls 3, and 1 is the floor of the mill on the delivery side of the rolls 2. The rod passes from the rolls 5 in a reflexed course to the rolls 4, thence to the rolls 3, and thence through the rolls 2, whence it passes in a direct line to the reel on which it is wound. There are more rolls than these generally used in a rod-mill; but I have shown a sufficient number to illus-

trate the principles of my invention. In its passage through these rolls the elongation of the rod forms loops a b , which, as they elongate, tend to spread over the floor, and it is the purpose of my invention to guide them, as I have already explained. One or both of these loops may be provided with guides according to my invention, and instead of arranging the guides differently they may be similarly arranged, as will be readily understood, since I have shown two modes of arrangement in the same mill simply for the purpose of more clearly illustrating my invention.

The floor 6 of the mill is inclined, as shown in Fig. 2, the inclination being greater than two degrees from the horizontal—say about six or more degrees—so that the wire loop as it elongates in passing from one pair of rolls to the next shall travel easily down the inclined floor without stopping or becoming kinked, and shall be impelled by the positively-acting motive force of the primary rolls 3 or 5. I believe that in order to accomplish this result satisfactorily it is necessary that the inclination should be greater than two degrees. I employ guide troughs or channels 7 and 8, leading from the delivery side of the rolls 3 and 5, for the purpose of guiding the loops a and b , the primary branches of which travel in the guides, while the other branches extend back to the rolls 2 and 4, respectively. I show the trough 8 set or sunk in the floor of the mill, so as to bring the top of the trough on a level with or to decrease its distance from the floor, thus preventing entirely or to a great degree the bending of the hot wire loop, and I show the guide 7 laterally inclined to the axes of the rolls, the purpose being to cause the branch of the loop to bear against the side of the guide, thus the better preventing it from flying over the floor. This lateral inclination also directs the loop over to a position on the floor more nearly opposite to the second pair of rolls, and thus causes the loop to take up less room on the floor. I also show the guide 7 set on the floor. The bottoms of both guides 7 and 8 are preferably flat, as shown in Fig. 4, since I have found this form the best for guiding the loops and preventing tangling when more than one rod is rolled at once. If desired, the mill-floor may be inclined on both sides of the rolls for the purpose of guiding the loops. I have shown it inclined on one side only, because that is sufficient to illustrate the principles of my invention.

At the delivery side of the rolls 2, and extending thence toward the reel, is a guide, 9, which is unlike the guides 7 and 8 in function, because it does not guide a loop of the rod, but the end of the rod passes directly through the guide 9. It is sunk in the floor of the mill, and in this way I render the overfeed of the wire less liable to bend and tangle.

10 are the guards or fenders which I employ for preventing the rear end of the rod

from flying upward or laterally as it passes through the rolls. The fender consists of an angled plate set with its upright side extending upward from the floor between the course 5 of the second branch of the loop and the position of the roller, and preferably having a cover extending over the loop. As the end of the rod emerges from the rolls 3 or 5, the roller seizes it with his tongs, throws the loop 10 over the cover of the fender, so that it shall fall to the floor beneath the cover, as shown in the drawings, and places the end of the loop in the pair of rolls 2 or 4. To make this operation easier, the fender is preferably downwardly tapered in height from the rolls, and 15 also inclined on the top laterally, as shown in Fig. 3. As the end of the rod passes through the rolls 2 or 4, the fender keeps it from flying up or toward the roller, who may therefore 20 with security stand by the rolls and reach over the passing rods for the purpose of inserting the forward end of an incoming rod into the bite of the rolls. The fender may be modified in form and size.

25 My invention is susceptible of modifications in various ways without departing from the principles thereof, as stated in the following claims. It may also be applied to mills for rolling hoop-iron. I desire to cover such uses 30 by the term "rod-mill."

I am aware of Letters Patent to McCallip, No. 331,516, dated December 1, 1885, and do not herein desire to cover, broadly, anything therein shown and described. In said patent 35 is shown the usual horizontal mill-floor, on which the rod-loop is received and distributed by "hooker-boys," and a short overfeed regulator is used in conjunction with a repeater simply to guide the loop to the level 40 of the horizontal floor, where it is received and drawn away from the rolls by the hooker-boys, there being in said patent no inclined mill-floor or other means whereby the gravity 45 of the loop and the force of the rolls are utilized to distribute the loop after it leaves the overfeed regulator.

I claim—

1. In a wire-rod mill, the combination, with the main mill-floor having an inclined surface which extends in a plane transversely to the rolls, substantially as described, of a series 50 of rolls arranged on different lines of feed, whereby the propelling force of the rolls and the gravity of the loop are utilized to cause the loop to travel freely over the floor, substantially as and for the purposes specified.
2. In a rod-mill, the combination, with the rolls and a receiving mill-floor, of an open guide through or channel sunk in the mill- 55 floor and extending from the rolls, substantially as and for the purposes specified.
3. In a rod-mill, the combination, with two

sets of rolls arranged on different lines of feed and the mill-floor, of an open sunken guide trough or channel arranged on the delivery 65 side of the primary rolls and leading therefrom for the purpose of guiding the primary branch of the loop, substantially as and for the purposes specified.

4. In a wire-rod mill, the combination, with the main mill-floor having an inclined surface extending in a plane transversely to the rolls, substantially as described, of a series of rolls arranged on different lines of feed, whereby the propelling force of the rolls and the 70 gravity of the loop are utilized to cause the loop to travel freely over the floor, and a guide extending along the said inclined main floor transversely to the delivery side of the primary rolls and adapted to guide the primary 75 branch of the loop, substantially as and for the purposes specified.

5. In a rod-mill, the combination, with two sets of rolls arranged on different lines of feed, of a mill-floor having a downwardly and 80 obliquely inclined guide extending along said floor from the delivery side of the primary rolls, substantially as and for the purposes specified.

6. In a rod-mill, the combination, with the 90 rolls, of a plate-fender arranged in the line of the feed, substantially as shown and described.

7. In a rod-mill, the combination, with two sets of rolls arranged on different lines of feed, of a plate guard or fender arranged in the circuit 95 between the rolls, substantially as and for the purposes specified.

8. In a rod-mill, the combination, with two sets of rolls arranged on different lines of feed, of an inclined plate guard or fender arranged 100 in the circuit between the rolls, substantially as and for the purposes specified.

9. In a wire-rod mill, the combination, with two sets of rolls arranged on different lines of feed, of a single branch guide trough or channel 105 having a flat bottom extending along the mill-floor from the delivery side of the primary set of rolls only and transversely therefrom and the mill-floor at the side of said guide trough or channel, whereby the primary 110 branch of the loop is confined and guided and permitted by the flat bottom to have a free course restricted laterally by the sides of the trough or channel, while the return branch is permitted to travel freely on the floor outside 115 the limits of the channel, substantially as and for the purposes specified.

In testimony whereof I have hereunto set my hand this 1st day of May, A. D. 1888.

HENRY ROBERTS.
